CONTROL DEVICE

Allen R. Davidson, Erie, Pa., assignor to Reliable
Radio Inc., Erie, Pa., a corporation of Pennsyl-
vania

Application March 31, 1945, Serial No. 585,878

7 Claims. (Cl. 192—130)

1

This invention relates to a control device actuated by the change in transmission of radio frequency energy between a pair of electrodes due to the presence of a foreign body in the field between the electrodes. One application is as a safety device for a machine where the operator must reach through the field between the electrodes to get to a danger zone. The interception of the field by the operator changes the signal received at one of the electrodes causing operation of the control to prevent injury to the operator. Further objects and advantages appear in the specification and claims.

In the accompanying drawing, Fig. 1 is an elementary diagram; Fig. 2 is a fragmentary view showing the electrodes arranged as a safety device for a molding press; and Fig. 3 is a control diagram.

The control device is actuated by changes in the field between transmitting and receiving electrodes 1 and 2 connected across a radio frequency transmitter 3. The transmitter is diagrammatically illustrated as having a center tapped output inductance 4, one end connected directly to the transmitting electrode and the other end connected through a coupling condenser 5 to the receiving electrode. The coupling condenser conducts an out of phase voltage to the receiving electrode substantially balancing the voltage received from the transmitting electrode. Since the electrodes are closely spaced, only the induction field radiation is transmitted to the receiving electrode. When the field between the electrodes is disturbed, the net radio frequency energy at the receiving electrode is changed, and this change is fed through an amplifier 6, a detector 7, to a relay 8 for performing the desired control function.

The shape and position of the electrodes will obviously vary with the control application. In Fig. 2 the control is shown applied to a molding press having a stationary platen 9 and a movable platen 10. The electrodes are arranged in front of the press to interpose a curtain-like field between the press and the operator. The transmitting electrode is in the form of a plate arranged edgewise to the press and spaced sufficiently in front of the press so that the field between the electrodes is negligibly affected by the movable platen. The receiving electrode is in the form of a rod similarly spaced in front of the stationary platen. The electrodes have a height slightly greater than the height of the platens so that an operator reaching between the platens must intercept the field between the

2

electrodes. In a practical application the electrodes have been spaced about three inches from the press and the spacing between the electrodes has been eighteen inches.

An operator reaching between the electrodes causes an increase in the radio frequency energy at the receiving electrode. This increase in energy is used to actuate the relay which may be a solenoid 11 having normally closed contacts 12 connected in the control circuit for closing the press, and contacts 13 connected in the control circuit to open the press. The increase in radio frequency energy at the receiving electrode causes the closure of the contacts 13 and the resultant opening of the molding press.

After the press is closed, the control is no longer necessary. The control is therefore disabled by a limit switch 14 mechanically connected with the movable platen so as to open contacts 15 when the press is closed. The opening of the contacts 15 prevents opening of the molding press by the closing of the contacts 13.

In the control diagram, the transmitter is shown as a three megacycle oscillator supplied by a full wave rectifier 16. The output circuit of the oscillator comprises a condenser 17 and the center tapped inductance 4, the center tap being connected to the high side of the power supply through an inductance 18. From one aspect the inductance 4, the condenser 5 and the electrodes 1 and 2 comprise a bridge circuit having pairs of inductive and capacitative arms connected in parallel across the radio frequency output of the transmitter. The condenser 5 is preferably adjusted so that the bridge is normally nearly balanced. Sensitivity is greater if the bridge is slightly to one side of the balance point. Unbalancing of the bridge caused by the operator reaching between the electrodes results in an increase in voltage at the receiving electrode which is coupled to the control grid 19 of the amplifier. The amplifier output appears in a tuned circuit 20 inductively coupled to a tuned circuit 21 in series with the detector 7. The detector output is taken from the cathode circuit from a condenser 22 shunted by a resistance 23. An increase in the radio frequency voltage at the receiving electrode 2 appears in the detector output as a positive voltage which is connected to the control grid 24 of a thyratron 25. The thyratron is connected in series with the solenoid release 11 across the secondary 26 of a transformer 27. The cathode 28 of the thyratron is connected to an adjustable tap 29 on a voltage divider 30 across the full wave rectifier 16. An additional

alternating bias voltage is connected to the grid from an adjustable tap 31 on a resistor 32 across an auxiliary winding 33 on the transformer 21. The tap 29 is adjusted so that the thyratron does not conduct under a normal condition of the control.

There is some slight change in the radio frequency energy at the receiving electrode due to changes in the position of the movable platen. The tap 29 is adjusted so that these changes do not affect the thyratron. When the operator reaches between the electrodes, the further increase in radio frequency energy at the receiving electrode causes a positive bias on the grid 24 which overcomes the bias from the tap 29 and fires the thyratron. This actuates the solenoid relay 11 opening the contacts 12 and closing the contacts 13. The opening of the contacts 12 prevents further closure of the press and the closing of the contacts 13 opens the press.

The control can be made very sensitive without becoming so sensitive as to result in nuisance operation. The control is made insensitive except in the field between the electrodes. The control will be actuated as soon as the operator's finger reaches the field between the electrodes. It will not be actuated by movement of the platen nor will it be operated if the operator's hand is placed quite close to the outside of either of the electrodes. For example, the operator's hand can be placed within a few inches of the transmitting electrode on the outer side without making any substantial change in the radio frequency energy received at the receiving electrode. This indicates that the control is almost wholly responsive to the field between the electrodes. By increasing the positive bias at the adjustable tap 29, the control may be made less sensitive. As the sensitivity is decreased the area of response between the electrodes is decreased until finally the control will be actuated only if the operator reaches through the center point of the field between the electrodes. Under these conditions the operator can take hold of either electrode without operating the control.

As the electrodes are spaced further apart, the operation is improved by connecting a condenser 34 across the electrodes. The condenser 34 couples an in phase voltage to the receiving electrode partially balancing the out of phase voltage from the condenser 5. In the specific application the condenser 34 was found desirable when the electrode spacing was increased from twelve to eighteen inches. In the particular application the condenser 34 permits the selection of a practical value for the condenser 5. It is not necessary in all applications.

The intensity of the field between the electrodes is greatest in the area bounded by lines of sight connecting the outside edges of the electrodes. There is a field of less intensity outside this area. By adjusting the sensitivity control it is possible to make the device respond to interception of the field in the area bounded by the electrodes, to interception of only the field at the central part of the area, or to interception of the lower intensity field outside the area. The adjustment depends upon the requirements of the application.

The shape of the electrodes also varies with the application. In the application illustrated, the receiving electrode is a rod because it is located near the normal position of the operator. The smaller area of the rod presented to the operator minimizes accidental operation of the safety device. If both electrodes were rods (or wires)

the sensitivity control would have to be adjusted for greater sensitivity and the part of the field responding to interception by the operator would be thicker (would bulge) at the center. This is not desirable for the application illustrated, where a zone of response of limited thickness is required to prevent nuisance operation of the safety device. For other applications a thicker zone of response may not be objectionable and may even be desirable.

By having the control respond to interception of the field between two electrodes rather than to interception of the field between one of the electrodes and ground, the operation is substantially independent of the intercepting body which may be grounded or insulated or isolated from ground without affecting the operation of the control.

What I claim as new is:

1. In a control circuit, a bridge having a pair of inductive and a pair of capacitative arms, a radio frequency supply connected across the bridge, one of the arms comprising a pair of spaced electrodes having a substantial impedance to ground and a radio frequency field on lines of sight therebetween in which the presence of a foreign body is to be detected, and a control responsive to the change in voltage across the electrodes due to the presence of a foreign body in the field.
2. In a control circuit, a radio frequency source having a center tapped output coil, a capacity divider across the coil, said capacity divider having a center terminal and on one side of the terminal a pair of electrodes having a substantial impedance to ground and a field on lines of sight therebetween in which the presence of a conducting or semiconducting foreign body is to be detected and on the other side of the terminal a balancing condenser, an amplifier for the voltage at the center terminal, and a control responsive to the amplifier output, said condenser being adjusted so the control is operated by the change in interelectrode capacity due to the presence of a foreign body in said field.
3. In a control circuit, transmitting and receiving electrodes spaced to provide a field in lines of sight therebetween affected by the presence of a foreign body, a radio frequency transmitter connected to the transmitting electrode, means coupling a radio frequency wave to the receiving electrode of phase opposite to the wave from the transmitter electrode substantially balancing the transmitted wave, a condenser coupling a radio frequency wave to the receiving electrode in phase with the transmitted wave, and means responsive to the change in the net radio frequency wave at the receiving electrode due to the change in the transmitted wave caused by a body intercepting the field.
4. In a control circuit, spaced electrodes having a substantial impedance to ground and energized by a radio frequency power source producing a radio frequency field on lines of sight therebetween in which the presence of a conducting or semi-conducting foreign body is to be detected, a bridge circuit having an arm including the electrodes, and a control responsive to change in the balance of the bridge caused by the presence of a foreign body in the field.
5. A safety device for a machine having a moving part, a pair of electrodes having a substantial impedance to ground and to said part and energized by a radio frequency power source producing a curtain like radio frequency field on

lines of sight between said electrodes and shielding said part from the operator, the electrodes being to one side of said part so the field is negligibly affected by the position of the part, a bridge having diametral terminals for connection to a radio frequency source and having an arm including the electrodes, and a control for the safety device responsive to the change in voltage at an intermediate terminal on the bridge due to the interception of said field by an operator.

6. In a control circuit, transmitting and receiving electrodes having a substantial impedance to ground and spaced to provide a radio frequency field on lines of sight therebetween affected by the presence of a foreign body, a radio frequency transmitter connected to the transmitting electrode and energizing the electrode at a substantially constant intensity and frequency, means coupling a radio frequency wave to the receiving electrode of phase opposite to the wave from the transmitter electrode, and means responsive to the change in the net radio frequency wave at the receiving electrode due to the change in the transmitted wave caused by a body intercepting the field.

7. A safety device for a machine having a danger zone, transmitting and receiving electrodes having a substantial impedance to the machine and to ground and spaced to provide a radio frequency field on lines of sight between the

danger zone and the operator, a radio frequency transmitter connected to the transmitting electrode, means coupling a radio frequency wave to the receiving electrode of phase opposite to the wave from the transmitting electrode, and means responsive to the change in the net radio frequency wave at the receiving electrode due to the change in the transmitted wave caused by a body intercepting the field for controlling the safety device.
